[57] **CLAIM**

The ornamental design for a combined fireplace gas log lighter and fuel container, as shown and described.

DESCRIPTION

FIG. 1 is a top front and left side perspective view of a combined fireplace gas log lighter and fuel container, showing my new design;

FIG. 2 is a top plan view thereof;

FIG. 3 is a right side elevation view thereof; and,

FIG. 4 is a bottom plan view thereof.

The rear of the log lighter is flat and unornamented.

FIG. 1

FIG. 2

FIG. 3

FIG. 4
